UNITED STATES PATENT OFFICE.

GEORGE H. F. SCHRADE, OF NEW YORK, N. Y.

DESIGN FOR A TIRE-VALVE CAP.

SPECIFICATION forming part of Design No. 31,830, dated November 14, 1899.

Application filed July 23, 1897. Serial No. 645,739. Term of patent 14 years.

To all whom it may concern:

Be it known that I, GEORGE H. F. SCHRADE, a citizen of the United States, residing in the city, county, and State of New York, have invented and produced a certain new and original Design for a Tire-Valve Cap, of which the following is a specification.

The new design relates to the shape of tire-valve caps, and especially to such as those of the general character shown in my Letters Patent for a "Design for a tire-valve cap," No. 25,774, dated July 14, 1896.

The new design is shown in the accompanying drawings, in which—

Figure 1 is a perspective view of the cap. Fig. 2 is a side elevation of the cap, looking at right angles to Fig. 1; and Fig. 3 is a top plan of the cap.

The distinctive features of the new design are, as shown in the drawings, a rough serrated side band A, a smooth annular top band B, a smooth round projection C, curved concave receding sides D at the upper end of said projection, and a straight parallel and narrow

top edge E between the sides D and crossing the upper end of the projection diametrically and at right angles to the axis of the cap. A smooth band F is shown below the band A. The protuberance C is shown as cylindrical and of a length approximately as great as the combined width of the bands A and F. It is of relatively small diameter compared with these bands. Its surface and the surfaces of the sides D are smooth, forming sharp angles where they join. The sides D are parallel with the edge E and extend therefrom downwardly, with a gradually-increasing outward curvature.

What I claim is—

The design for a tire-valve cap, substantially as shown and described.

In witness whereof I have hereunto signed my name in the presence of two subscribing witnesses.

GEO. H. F. SCHRADE.

Witnesses:

GEORGE H. FRASER,
THOMAS F. WALLACE.
